UNITED STATES PATENT OFFICE

HERMON P. OBER, OF ROCHESTER, NEW YORK, ASSIGNOR TO GENERAL RAILWAY SIGNAL COMPANY, OF ROCHESTER, NEW YORK

RAILWAY SIGNALING SYSTEM

Application filed June 22, 1928. Serial No. 287,394.

This invention relates in general to a railway signal system, and has more particular reference to a signal for controlling trains at station platforms.

5 In the operation of railway trains, and in subway operation in particular, it is desirable to limit the time a train should occupy the track adjacent the loading and unloading platforms, in order to expedite traffic and 10 avoid confusion at platform locations.

With the above object in mind, it is proposed in accordance with this invention to provide automatic means for giving a signal when a train can be expected to leave a loading platform, with means for initiating the signal only after the train has been along side the loading platform for a predetermined time, together with automatic means for cutting out the signal.

20 More specifically, this invention provides means whereby, after a train has been brought along side a loading platform, a time element relay is energized, which relay, after a predetermined time interval, as for example 25 25 seconds, is effective to energize a signal, such as an electric bell. Upon energization of the signal, time element, such as a thermally controlled device is caused to function, and is effective after a predetermined time interval,

30 as for example 5 seconds, to de-energize and thereby silence the bell. In this manner a 30 second time interval is allotted to a train at a platform, with a signal given during the last five seconds of the allotted time, to warn 35 the traveling public, and advise the train crew that on silencing of the signal, the train should be operated to clear the section of track adjacent the loading platform.

Further objects, purposes, and characteristic features of the present invention will 40 appear as the description progresses, reference being had to the accompanying drawing, given wholly by way of example and not in any manner in a limiting sense, where-

45 in:— The single figure of drawing represents, in a wholly diagrammatic manner, one form which applicant's invention can assume.

Referring now to the drawing, there is 50 shown a stretch of track, including track rails

1, divided by means of insulating joints 2, into separate insulated track sections or blocks A, B, etc. Each track section or block includes a source of energy such as a track transformer connected to an A. C. supply, or a battery 3 55 connected across the rails at one end of the block, and a track relay T connected across the track rails at the other end of the block. At the entrance end of block B, traffic being assumed to be in the direction of the arrow, 60 is positioned a traffic signal shown as a light signal but which can, of course, be of any other desired type such as a semaphore or the like. This signal 4 is controlled in an automatic manner, in accordance with traffic, in 65 any desired or known way, such for example as shown in the Peabody Patent 1,627,453 granted May 3, 1927, it being deemed unnecessary for the purpose of the present invention, to show, or further describe, the signal control. 70

Positioned along side the tracks of block B is a loading and unloading platform 5, such for example as is very generally employed in connection with subway lines. 75

Included in this invention is a main control relay 6, a signal S, a signal cut out relay 7, and a thermal relay R.

The main control relay 6 is preferably an alternating current relay, although of course 80 a direct current relay could be employed, and includes a time element, preferably of the mechanical type, whereby the relay moves its contact fingers 9, 10 and 11 to attracted position only after the lapse of a predetermined 85 time after it is energized, in the present case approximately 25 seconds. Relay 6 is quick releasing so as to release its contact fingers immediately on de-energization.

The cut-out relay 7 is shown as an alternating current relay and reasonably quick to pick up and release, and is furnished with two contact fingers 12 and 13.

The signal S is shown as an electric bell of any known or desired type, which gives an 95 audible signal on energization and is silenced on de-energization. This signal can however just as well be any other type of audible signal such as a horn or the like or could be a visual or other kind of signal if desired. 100

The thermal relay R includes an insulating base 14, having relatively stiff conducting arms 15 and 16 connected thereto and normally positioned to have their contacts 17 spaced apart, there being a heating coil 18 carried on the arm 16 and connected electrically to the arm 16 at its two ends. Connected to the heating coil 18 at its central point, is a conductor 19, the coil 18 functioning when energized to heat the arm 16 and cause it to move to bring the contacts 17 together. The heating coil 18, can, of course be end fed and connected at but one end to the arm 16, if desired, or any other desired connection can be employed.

The arrangement shown also includes a resistance 8 which is considerably less than the resistance of the relay 7, (in one satisfactory arrangement, the ratio being 2 to 3), for purposes which will be clear as the description progresses. If alternating rather than direct current be employed, this member 8 will be an impedance bearing the same relation to the impedance of the relay 7 as just set forth.

In order to simplify the wiring diagram, the letters B and C are employed to represent the opposite terminals of a source or sources of electrical energy of either direct or alternating current.

The invention will perhaps be most readily understood by describing its operation through one complete cycle.

Assume a train moving on the track rails 1 in the direction of the arrow. On occupancy of the approach block A, track relay T^o becomes de-energized and releases its contact finger 20. As the train progresses and occupies the platform block B, track relay T becomes de-energized and releases its contact finger 21. Thus far this progress of the train has had no effect upon the platform signal apparatus, and it is only after the rear end of the train has passed wholly out of the approach block A, so as to re-energize track relay T^o, that a pick up circuit is completed for the main control relay 6 which circuit can be traced as follows:—from one terminal B of a source of energy, contact finger 21 and back point of relay T, contact finger 20 and front point of relay T^o, the winding of relay 6, to the opposite terminal C of a source of energy.

As described above this relay 6 is furnished with a time element which causes the relay fingers, 9, 10 and 11 to be moved to attracted position, only after 25 seconds after energization. Relay 6 now remains energized regardless of whether or not approach block A be occupied, through a stick circuit which includes in series, contact finger 9 and front point of relay 6, and contact finger 21 and back point of relay T, the remaining portions of this stick circuit being obvious from the drawing.

As soon (25 seconds after relay 6 is energized) as contact finger 10 of relay 6 is moved to attracted position, an energizing circuit for the bell signal S is completed which includes in series contact finger 10 and front point of relay 6, and contact finger 13 and back point of the cut-out relay 7.

Movement of contact finger 11 of relay 6 to attracted position completes an energizing circuit for the coil 18 on thermal relay R which circuit includes, contact finger 11 and front point of relay 6, wires 22 and 19, coil 18, arm 16, wire 24, contact finger 12 and back point of relay 7 and the resistance unit 8. It will be noted that this coil 18 of the thermal relay R is energized simultaneously with the energization of the signal S.

As described above, energization of the heating coil 18 causes the contacts 17 to come into contact approximately 5 seconds after such energization, which results in completing a pick up circuit for the cut out relay 7 which circuit includes contact finger 11 and front point of relay 6, wires 22 and 19, coil 18, contacts 17 in closed position, arm 15, wire 23, and the winding of relay 7. Upon energization, relay 7 moves its contact fingers 12 and 13 to attracted positions.

Raising of contact finger 13 of cut out relay 7 breaks the energizing circuit for the signal S which results in silencing the signal.

The movement of contact finger 12 of relay 7 to attracted position breaks the energizing circuit for heating coil 18 of thermal relay R, which passes through the resistance unit 8, as traced above, and at the same time completes a stick circuit for relay 7 which includes the winding of relay 7, contact finger 12 and front point of relay 7, wire 24, arm 16, winding 18 of thermal relay R, wires 19 and 22, and contact finger 11 and front point of control relay 6. It will be seen that the heating coil 18 of the thermal relay R is still energized but that it is now in series with the winding of relay 7 and that, as described above, the resistance of the winding of relay 7 is considerably greater than that of the resistance unit 8, whereby insufficient current flows through the heating coil 18 to maintain the contacts 17 closed so that the arm 16 immediately begins to cool off.

On silencing of the signal S after it has sounded for 5 seconds as described above, the train crew is advised that the train should start, and the travelling public has been warned, and upon the rear end of the train passing out of the platform block B, track relay T will pick up and thereby break the stick circuit for control relay 6, at the contact finger 21 of track relay T. Control relay 6 immediately releases its contact fingers 9, 10 and 11, the contact finger 9 breaking the stick circuit for relay 6 at a second point, the contact finger 10 breaking the energizing circuit for the signal S at a

second point, and the contact finger 11 breaking the stick circuit for relay 7, and also breaking the pick up circuit for this relay 7, which would otherwise be closed if contacts 17 of thermal relay R had not yet opened. Thus all the various parts are restored to normal position as shown in the drawing.

It should be noted that signal 4, if observed, prevents entrance of a following train into block B until after this block has been cleared by the forward train so that it is insured that track relay T shall release upon the forward train clearing block B to thereby restore the various parts of the system to normal.

By having the stick circuit for relay 6 independent of the track relay T, occupancy of the advance block A, while a train is in block B, cannot interfere with the operation of the system.

As brought out above, by having the resistance 8 considerably less than that of the winding of relay 7, the heating coil 18 of thermal relay R begins to cool off as soon as relay 7 has picked up which is, of course, a desirable feature since it is necessary that the contacts 17 of relay R be open by the time a following train has moved along side the platform 5 sufficiently to have its rear end clear the approach block A.

The above rather specific description of one form of this invention has been given solely by way of illustration, and is not intended, in any manner whatsoever, in a limiting sense. Obviously, the invention can assume many different physical forms, and is susceptible of various modifications, and all such forms and modifications are intended to be covered by the present invention, as come within the scope of the appended claims.

Having described my invention, I now claim:—

1. In a signal system, a section of track divided into insulated blocks, a signal, control means effective on occupancy of one of said blocks, only if another of the blocks be unoccupied, to initiate said signal, and a signal cut out means initiated by said control means and effective a predetermined period of time after initiation to render said signal inactive.

2. In a signal system, a section of track divided into insulated approach and platform blocks, a signal, control means effective on occupancy of said platform block if said approach block be unoccupied to initiate said signal, a signal cut out means initiated by said control means and effective a predetermined period of time after initiation to render said signal inactive.

3. In a signal system, in combination, a section of track divided into insulated approach and platform blocks, a normally inactive signal, a control relay operable a pre-

determined time after energization to make said signal active, and means energizing said control relay on occupancy of said platform block only if said approach block be unoccupied.

4. In a signal system, in combination, a normally inactive signal, a control relay operable a predetermined time after energization to make said signal active, and a signal cut out means initiated substantially at the time said signal is made active and effective a predetermined time after initiation to make said signal inactive.

5. In a signal system, in combination, a normally inactive signal, a control relay operable a predetermined time after energization to make said signal active, a thermal cut out means for said signal energized by said control relay at the time said signal is made active, said cut out means operating a predetermined time after energization to make said signal inactive.

6. In a signal system, in combination, a platform, a section of track adjacent said platform, a signal, control means effective only a predetermined time after occupancy of said section of track to initiate said signal, and a signal cut out relay initiated simultaneously with said signal and effective a predetermined time after initiation to cut out said signal.

7. In a signal system, an insulated section of track, a signal, a control relay energized on occupancy of said section and effective only a predetermined time after energization to initiate said signal, a signal cut out relay, a thermal relay energized by said control relay simultaneously with the initiation of said signal, and a circuit controlled by said thermal relay a predetermined time after energization of the thermal relay to cause said cut out relay to assume its signal cut out position.

8. In combination, in a signal system, a section of track divided into insulated approach and control blocks, a track relay for each of said blocks, a signal, a control relay for energizing said signal having a pick up circuit including in series a front point and a back point, respectively, of said track relays and a stick circuit including a back point of said control block track relay but not of said approach block track relay, and means controlled by said control relay for de-energizing said signal.

9. In combination, in a signal system, a section of track divided into insulated approach and control blocks, a track relay for each of said blocks, a signal, a control relay for energizing said signal having a pick up circuit including in series front and back points, respectively, of said track relays and a stick circuit including a back point of said control block track relay but not of said approach block track relay, a thermal relay, and

a cut out relay for de-energizing said signal having a pick up and a stick circuit each including a front point of said control relay, said pick up circuit for said cut out relay

5 also including contacts of said thermal relay.

10. In combination, in a signal system, a section of track divided into insulated approach and control blocks, a track relay for each of said blocks, a signal, a control relay for energizing said signal having a pick up circuit including in series a contact point of each of said track relays and a stick circuit including a contact point of but one of said track relays, a thermal relay, and a cut out

15 relay for de-energizing said signal having a pick up and a stick circuit each including a front point of said control relay, the pick up circuit for said cut out relay also including contacts of the thermal relay, said thermal

20 relay including a heating coil having an energizing circuit including in series a front point of said control relay and a back point of said cut out relay.

11. In combination, in a signal system, a section of track divided into insulated approach and control blocks, a track relay for each of said blocks, a signal, a control relay for energizing said signal having a pick up circuit including in series front and back

30 points, respectively, of each of said track relays and a stick circuit including a back point of said control block track relay but not of said approach block track relay, a thermal relay having normally open contacts, a cut

35 out relay for de-energizing said signal and having a pick up, and a stick circuit, each circuit including a front point of said control relay, said pick up circuit for said cut out relay including said contacts of said thermal

40 relay, and a heating coil in said thermal relay which, when energized, closes said normally open contacts and having an energizing circuit including in series a front point of said control relay and a back point of said

45 cut out relay.

12. In a signal system, in combination, a platform, a section of track adjacent said platform, a signal, control means effective only a predetermined time after occupancy

50 of said section of track to initiate said signal, and a signal cut out relay effective a predetermined time after initiation to cut out said signal.

In testimony whereof I affix my signature.

55 HERMON P. OBER.
